F. H. EYBEN.

COMBINATION HARROW CART.

FILED JUNE 9, 1920.

INVENTOR
FRANK H. EYBEN,
BY ATTORNEY

E.W. Bond

UNITED STATES PATENT OFFICE.

FRANK H. EYBEN, OF CUMMINGS, ALBERTA, CANADA.

COMBINATION HARROW CART.

Application filed June 9, 1920. Serial No. 387,738.

To all whom it may concern:

Be it known that I, FRANK H. EYBEN, a citizen of the British Empire, residing at Cummings, in the county of Strathcona and Province of Alberta, Canada, have invented certain new and useful Improvements in Combination Harrow Carts, of which the following is a specification.

This invention relates to harrows, and 10 has for its particular object a means for lifting the harrow when traversing to and from the field.

A further object is to provide a means whereby each section of the harrow may be 15 lifted individually so as to allow grass and other undesirable material to fall off the teeth when in operation.

With these and other objects in view, the 20 invention consists in the construction, combination and arrangement of parts as will be hereinafter fully described, illustrated in the accompanying drawings, and pointed out in the claim hereunto appended.

Figure 1 is a top plan view of my invention, and

Fig. 2 is a sectional view showing the details of the same, parts shown in dotted lines.

Referring to the drawings like numerals 30 designate like parts in the various drawings. 3 is an axle on which are mounted suitable wheels 4. Suitably attached to the said axle and above the same is a runner 5 which is preferably made of a strip of wood. On this runner 5 is mounted a suitable seat holder 6 on which is positioned a seat 7.

Fastened at the ends of the runner 5 are 40 forwardly extending braces 8 which braces are attached to a front strip 9. Hingedly or otherwise connected to this strip 9 are sets of harrows 10 with the usual teeth extending downwardly from their lower sides. Each of the braces 8 is provided with a 45 looped end 11 at the forward end to which any suitable coupling means may be attached for draft purposes.

One of the braces 8 is positioned centrally as shown in Fig. 1, and on this brace is provided an upwardly extending arm 12,

the upper end of which is provided with three rollers 14. At the rear end of each 50 harrow I provide an eye-bolt 15 to which is attached one end of a rope 16. The ropes 16 extend up through eye-bolts 17 which are suitably positioned at the rear side of the runner 5. The ropes 16 then pass over 55 their respective pulleys 14 and have suitable rings 18 attached at their ends so that the operator can pull the ring 18 of any particular section from his seat and by so doing lift the rear end of the section up till 60 it comes under the axle 3 allowing any refuse to be discarded.

From this it will be noted that any or all sections may be pulled up as desired and from the construction of my frame used in 65 this harrow, I eliminate any unnecessary parts so as to lighten the load to the lowest possible extent.

From the foregoing it is thought that the 70 construction of my invention will be clearly understood, and, therefore, a more extended explanation has been omitted.

What I claim as new, is.—

A harrow consisting of certain sections with the usual teeth extending downwardly 75 therefrom, said sections being connected to a front strip, an axle, wheels mounted on said axle, a second strip covering said axle, braces extending from said front strip to said second strip, a seat mounted on said 80 second strip, an arm extending up from one of said braces, a number of pulleys positioned at the upper end of said arm, eye-bolts positioned at the rear of said sections, ropes connected to said eye-bolts and passing 85 through their respective said pulleys, rings on the end of said ropes for pulling the rear of the respective sections upwardly as desired and a means attached to said front strip for attaching the same to draft means. 90

In testimony whereof I affix my signature in the presence of two witnesses.

FRANK H. EYBEN.
